STAMPED-METAL ACCESS PLATE FOR GEARBOXES

Henry B. Chatfield, Kinsman, Ohio

Application January 8, 1951, Serial No. 204,990

10 Claims. (Cl. 220—46)

This invention relates to a process and the product of a process for manufacturing stamped-metal access plates for gear boxes, transmission casings, pumps, reactors, pressure vessels and similar movable and immovable units making use of a housing of some suitable kind in which a tight seal is desired between the housing and the access plate.

Heretofore, access plates for these purposes have ordinarily been made in the form of castings of malleable iron, steel, etc. In addition to being heavy, such plates have the disadvantage of requiring extensive machining, particularly on their seating surfaces; that is to say, those surfaces which overlie the edges of the access opening in the housing but as a rule are separated from them by a thin gasket and by which, with the aid of conventional fastening elements, the access plate is located and held in place on the housing. Such access plates are relatively expensive to manufacture. Up to the present time, savings of impressive proportions in materials and costs have been sacrificed that would have been enjoyed if satisfactory access plates could have been made of metal stampings; however, it has not heretofore been known how to make stamped-metal access plates that would give the desired sealing action between the seating surfaces on the access plate and the cooperating surfaces on the housing.

Previous attempts to manufacture stamped-metal access plates, of which there have been many, have been aimed at obtaining a seal by maintaining the sealing surface flat within one or two thousandths of an inch; this has resulted in excessive scrap, excessive die maintenance, or the addition of a surface grinding operation.

It is an object of the present invention to provide a stamped-metal access plate, and in some aspects of the invention an access plate that is built up of a plurality of metal stampings, that may be used in lieu of the cast-metal access plates of the kinds heretofore generally employed. It is a further object of the invention to provide a stamped-metal access plate that will give the desired sealing action, this even when substantial pressures must be resisted. It is a further object of the invention to provide a stamped-metal access plate that permits a substantially constant sealing pressure to be maintained at all points along the sealing surface. It is still a further object of the invention to reduce the cost of access plates to a minor fraction of the cost of cast-metal access plates of the kinds heretofore used. Other objects and advantages of the invention will be apparent from the description which follows, as well as from the accompanying drawings.

In the drawings, Figure 1 is a top plan of the preferred type of access plate showing the same after the channel-like structure encompassing the body portion of the access plate has been struck from the blank. Figure 2 is a section on line 2—2 of Figure 1 looking in the direction of the arrows. Figure 3 is a top plan of the access plate at a later stage in the process of manufacture. Figure 4 is a section similar to that of Figure 2 on line 4—4 of Figure 3. Figure 5 is a top plan of the access plate at a still later stage in the process of manufacture. Figure 6 is a top plan of the access plate in finished form. Figures 7 and 8 are sections similar to the section of Figure 2 but on lines 7—7 and 8—8 of Figures 5 and 6, respectively. Figure 9 is a bottom plan of the finished access plate of Figure 6.

By contrast with Figures 1 to 9, all of which are on a reduced scale, Figures 10 to 14 are of full size. Figure

2

10 is a view partly in vertical central section and partly in side elevation of the preferred type of access plate applied to the top of a gear box. Figure 11 is a view partly in vertical central section and partly in side elevation of a modified form of an access plate, likewise applied to a gear box. Figure 12 is a detail of the modified form of access plate seen in end elevation as if from the left hand end of Figure 11. Figure 13 is a similar view of the channel forming part of the modified form of access plate. Figure 14 is a transverse vertical section with parts in elevation through an access plate of the oil-pan type that is formed in a manner otherwise analogous to that of the preferred type of access plate of Figures 1 to 10, inclusive.

15 The access plate shown in finished form in Figures 6, 8 and 10 is shown also in applicant's copending application Serial No. 204,989, filed January 8, 1951, for "Access Plate."

In the form in which it is shown in Figures 1 and 2, the preferred type of access plate, generally designated 1 in Figures 1 to 9, inclusive, is in an early stage in the process of its manufacture. At this stage, a flat sheet-metal blank of appropriate shape has been given preliminary form by subjecting it to the action of two cooperating dies, male and female. It has a flat body portion 2 that as shown is polygonal but may be of any other desired shape; e. g., rectangular, square, circular, etc. Body portion 2 is surrounded by an encompassing peripheral channel 3 that has been struck up from the blank by the action of the dies. As appears from Figure 2, peripheral channel 3 is generally U-shaped in cross-section, being characterized by an inner wall 4 rising abruptly from body portion 2, an intermediate portion 5 extending outwardly in a manner permitting it to serve as the bottom portion or base of channel 3, and an outer wall 6 paralleling inner wall 4. Depending from outer wall 6 below the plane of body portion 2 are flash-like ears 7 which are removed by a suitable operation, such as pinch-trimming.

40 After the incompletely formed access plate has been trimmed to eliminate ears 7, it is worked between a second pair of cooperating dies to re-strike peripheral channel 3 to the desired finished size. In this same operation, locating bosses 9 are formed in inner wall 4 of channel 3, such bosses projecting toward the interior of the access plate in the manner most clearly shown in Figure 3. In the same operation, or, if desired, by a separate operation, those portions of the access plate at which inner wall 4 of channel 3 impinges on body portion 2 are deformed, as by pressure applied from above by a die, to form a smoothly-faired convex or downwardly bowed portion 10 in the stretches between adjacent bosses 9.

Such convex portions 10 usually have a radius of curvature so great that the convexity is almost imperceptible to the eye; nevertheless, each of them as viewed in side elevation presents the general configuration of a shallow catenary or like curve. Convex portions 10, which appear in exaggerated fashion in Figure 4 and subsequent figures, will ordinarily have a maximum height of more than about 0.001 but less than about 0.090 inch, measured from the proximate plane of body portion 2. The precise value, which is a function of the pressure to be retained, the distances between fastening elements and the nature of the fastening elements themselves, should be less than that amount which would give rise to permanent flattening as a result of the imposition of forces exceeding the elastic limit of the metal upon application of the fastening elements to the access plate.

70 The result of forming convex portions 10 is to introduce into what may be regarded as the edge of inner wall 4 of peripheral channel 3 a plurality of widely spaced longitudinally extending undulations; such undulations being of maximum height, measured from the proximate plane of body portion 2, approximately mid-way between each two adjacent bosses 9. Although, as indicated above, preferred practice involves forming convex portions 10 in the same operation in which peripheral channel 3 is re-struck and bosses 9 are introduced into its inner wall, the undulations may, if desired, be developed in any other desired way or at some other stage in the

process of manufacture of access plate 1. Usually, however, it will be desirable to form the undulations before undertaking the operations described hereinafter.

Convex portions 10 having been formed in some suitable way, the next following operation may conveniently be the operation of forming outwardly of bosses 9 the flat portions 11 ("flats") which appear in Figure 5 and subsequent figures. This likewise is done by means of cooperating dies. Simultaneously therewith, it is convenient to coin the opposite face of access plate 1. Such coining operation is for the purpose of providing smooth surfaces on those portions of access plate 1 underlying inner wall 4 of channel 3; i. e., those portions of access plate 1 at which peripheral channel 3 impinges on body portion 2.

In the course of the coining operation, a groove 13 (Figure 6) is produced on the top face of the access plate and smooth seating surfaces 14 (Figure 9) are developed on the bottom face of the access plate. The coining operation should not be carried so far as to destroy the catenary-like curves of convex portions 10; however, a small part of the original convexity is of course eliminated by the coining step. The amount of material removed is important in the sense that enough convexity must remain so that the convexity, measured from the proximate plane of body portion 2, exceeds the aggregate of the manufacturing tolerances on the opposed portions of the housing, access plate, and gasket.

After introducing flats 11 and performing the coining operation giving rise to grooves 13 and seating surfaces 14 on the obverse and reverse sides of access plate 1, respectively, means for attaching the access plate to the housing are incorporated in it. While various ways of attaching the access plate to the housing may be employed, preferred practice involves the introduction of openings of suitable size and shape, such, for example, as circular holes 12, one at the geometrical center of each of flats 11. This may be done by piercing, punching or in any other suitable way, giving the finished access plate, viewed from above, the appearance indicated in Figure 6. Viewed from below, the finished access plate has the appearance presented by the bottom plan constituting Figure 9 of the drawings. In a typical case, the access plate illustrated on a somewhat reduced scale in Figures 1 to 9 has an overall length, measured from side to side in Figure 6, of approximately 5 inches and an overall width of approximately 4½ inches. Channel 3 may have an overall height of about ¾ inch, measuring from the bottom of body portion 2 to the top of channel 3. The width of channel 3 at its edges; that is to say, the width of the opening as measured in the plane of body portion 2, may be of the order of about ¼ inch. Hole 12 in flats 11 adjacent bosses 9 may in such case be spaced about 2½ inches from each other. Obviously, all of these dimensions and the ratios between them may be varied within very wide limits.

The preferred type of access plate is of sheet steel of relatively heavy gauge; e. g., 13-gauge, and of one of the many compositions lending themselves to stamping and use in access plates of the kind described, although it may, if desired, be formed of suitable non-ferrous metal.

Figure 10 shows access plate 1 applied to a gear box 15 having an opening 16 through which access may be had to the interior of the gear box. Extending upward from gear box 15 are studs 17, the same being suitably located around the periphery of opening 16. Onto studs 17 are threaded the nuts 18, the latter seating on flats 11 adjacent locating bosses 9. Between the access plate and the gear box is a gasket 19, which may be made of oil-impregnated kraft paper about .010 inch in thickness. In seating on gear box 15, the convex portions of the access plate giving the undulatory effect to the seating surface come first into contact with the gasket 19 approximately mid-way of the stretches between studs 17; thereafter, as nuts 18 are screwed home, the other portions of the seating surface of the access plate, including those in which locating bosses 9 are formed, come progressively into contact with the gasket, compressing it again gear box 15.

The modified form of access plate shown in Figures 11 to 13 is made up of two metal stampings, one of them a substantially flat sheet 21, provided, if desired, with one or more reinforcing ribs 22, which sheet serves as the body portion of the access plate. Impinging upon body portion 21 is the separately formed peripheral channel

23, the same being generally U-shaped in cross-section and consisting of an inner wall 24, an outer wall 25, and a substantially flat connecting portion 26. Channel 23 is formed with spaced indentations 27 in its inner and outer walls, such indentations locating the means for positioning and attaching the fastening elements (studs 17 and nuts 18) that hold the access plate to gear box 15. Such means include registering openings in gasket 19, body portion 21 and connecting portion 26 between inner wall 24 and outer wall 25.

The edge of inner wall 24, and, if desired, also the edge of outer wall 25, is bowed between adjacent openings in a manner analogous to the bowing provided by convex portions 10 in the access plate of Figures 1 to 10, inclusive. Although shown in greatly exaggerated fashion, the bowing of the edge of inner wall 24 appears at 24a in Figure 13, which represents a channel in which the edge of the inner wall is bowed and the edge of the outer wall is not bowed. This bowing of the edge of the inner wall 20 of the encompassing structure is communicated to body portion 21. When the built-up access plate of Figure 11 is applied to gear box 15, sealing action is obtained both where the bowed portions overlie the edges of access opening 16 and where nuts 18 on studs 17 urge the parts together.

For the purpose of holding channel 23 in place on body portion 21, the latter is provided at each end with a projection 28 which carries an inwardly extending tang 29. Tangs 29 are preferably integral with projections 28 and 30 the latter are preferably integral with body portion 21. When the parts are assembled to form the access plate, each tang 29 is forced into a recess 30 in outer wall 25 of peripheral channel 23, thus providing a mechanical interlocking of the parts as indicated, for example, in Figure 12. While this construction may be used not only at the ends but also along the sides of the access plate, two are sufficient in an ordinary case to hold peripheral channel 23 firmly in place on body portion 21.

If desired, in each of these embodiments of the invention, the outer wall of the peripheral channel may be interrupted or even largely eliminated, leaving an encompassing structure that may nevertheless be described as channel-like in the sense that when the access plate is applied to a gear box or the like, the resulting open-sided 45 hollow has the characteristics of a laterally extending or outwardly facing channel.

In each of the forms of the invention heretofore described, the encompassing structure is of a height greater than the maximum height of the intervening body portion. It is of course possible to have the body portion 50 raised above or depressed below the encompassing structure. This is illustrated in Figure 14, which shows an integrally formed access plate of the oil-pan type, such access plate being applied to a housing 32 having an opening 33 from which it is separated from a gasket 34 and to which it is affixed by bolts 35. The body portion 35 of the access plate is offset from the seating surfaces at the edge of the inner wall of the channel. Between side wall 37 and the channel is a hollow 38 into which the tool used in the coining operation enters when the seating surfaces are formed.

Thus the invention provides a stamped-metal access plate in which sealing contact with the gasket or, lacking a gasket, with the housing itself is established first approximately midway of the stretches between adjoining fastening elements. As the fastening elements are made tight, those portions of the access plate which do not make such contact initially; e. g., the portions of the access plate adjacent the fastening elements, are urged progressively into position, this being possible because of the inherent resilience of the metal itself. A substantially constant sealing pressure thus may be achieved and maintained along the entire sealing surface. If desired, however, the overall amplitude of the undulations as measured from the body portion of the access plate can be increased to a point where the pressure, disregarding manufacture tolerances, is greater mid-way between fastening elements than elsewhere, this being the precise opposite of the condition that obtains in ordinary access plates of the kinds heretofore used.

It is apparent that numerous modifications and departures may be introduced into the stamped-metal access plates described in the foregoing specification. The preferred construction is an integral construction of the kind illustrated in Figures 1 to 10 and 14. However, as

illustrated in Figures 11 to 13, a stamped access plate may, if desired, be formed of a plurality of separate sheet metal stampings. Elaborated forms of the invention made up of several such sheet metal stampings may readily be devised. As a general rule, they also will be characterized by a convexity or bowing providing a series of spaced undulations where the encompassing structure impinges upon or joins the body portion of the access plate.

It is intended that the patent shall cover, by summarization in the appended claims, whatever features of patentable novelty reside in the invention.

What is claimed is:

1. A stamped-metal access plate for a gear box or the like comprising a sheet metal stamping having a body portion; a seating portion on one side of the stamping near the periphery of the body portion, said seating portion being characterized by the presence therein of a succession of longitudinally extending undulations each of which is smoothly faired into the preceding and following undulations; and, on the opposite side of the stamping, a channel characterized by an inverted U-shaped cross-section having its bottom portion raised above the seating portion and in it integrally formed means adapted to receive the elements used in fastening the access plate in position, said integrally formed means and said seating portion being spaced from each other with the former offset from the latter in that direction which leads away from the interior of the gear box.

2. An access plate as in claim 1 in which the channel is formed separately from the rest of the access plate.

3. A stamped-metal access plate for a gear box or the like comprising a sheet metal stamping having a body portion; a seating portion on one side of the stamping near the periphery of the body portion, said seating portion being characterized by the presence therein of a succession of longitudinally extending undulations each of which is smoothly faired into the preceding and following undulations; and, on the opposite side of the stamping, a channel characterized by an inverted U-shaped cross-section having its bottom portion offset from the general plane of said seating portion in that direction which leads away from the interior of the gear box and having in it integrally formed means accommodating the elements used in fastening the access plate to the gear box.

4. A stamped-metal access plate for a gear box or the like comprising a sheet metal stamping having a body portion; a seating portion on one side of the stamping near the periphery of the body portion, said seating portion being characterized by the presence therein of a succession of longitudinally extending undulations each of which is smoothly faired into the preceding and following undulations; and, on the opposite side of the stamping, a channel characterized by an inverted U-shaped cross-section, which channel impinges upon the body portion of the access plate along the edge portion of its outer wall, the bottom portion of said channel being offset from the general plane of said seating portion in that direction which leads away from the interior of the gear box and having in it integrally formed means accommodating the elements used in fastening the access plate to the gear box.

5. A stamped-metal access plate for a gear box or the like comprising a sheet metal stamping having a body portion; a seating portion on one side of the stamping near the periphery of the body portion, said seating portion being characterized by the presence therein of a succession of longitudinally extending undulations each of

which is smoothly faired into the preceding and following undulations; and, on the opposite side of the stamping, a channel characterized by an inverted U-shaped cross-section which channel impinges upon the body portion of the access plate both along the edge portion of its inner wall and along the edge portion of its outer wall, the bottom portion of said channel being offset from the general plane of said seating portion in that direction which leads away from the interior of the gear box and having in it integrally formed means accommodating the elements used in fastening the access plate to the gear box.

6. An access plate as in claim 5 in which the body portion and the channel are held together in the desired relation to each other by means of extensions on one which project into recesses in the other.

7. An access plate as in claim 6 in which the channel is provided with recesses in which are received reversely bent tangs formed integrally with the body portion.

8. A stamped-metal access plate for a gear box or the like comprising a sheet metal stamping having a body portion; an undulatory seating portion on one side of the stamping near the periphery of the body portion; and, on the opposite side of the stamping, a channel having an inverted U-shaped cross-section the bottom of which channel is offset from the general plane of said seating portion in that direction which leads away from the interior of the gear box, said channel impinging upon the body portion of the access plate along the edge portion

30 of the inner wall of the channel and having outwardly of said inner wall a series of openings for receiving the elements used in fastening the access plate to the gear box.

9. A stamped-metal access plate for a gear box or the like comprising a sheet metal stamping having a body portion; an undulatory seating portion on one side of the stamping near the periphery of the body portion; and, on the opposite side of the stamping, a channel having an inverted U-shaped cross-section the bottom of which channel is offset from the general plane of said seating portion in that direction which leads away from the interior of the gear box, said channel impinging upon the body portion of the access plate along the edge portion of the outer wall of the channel and having inwardly of said outer wall a series of openings for receiving the elements used in fastening the access plate to the gear box.

10. A stamped-metal access plate for a gear box or the like comprising a sheet metal stamping having a body portion; an undulatory seating portion on one side of the stamping near the periphery of the body portion; and, on the opposite side of the stamping, a channel having an inverted U-shaped cross-section the bottom of which channel is offset from the general plane of said seating portion in that direction which leads away from the interior of the gear box, said channel impinging upon the body portion of the access plate both along the edge portion of the inner wall and along the edge portion of the outer wall of the channel and having between said inner wall and said outer wall a series of openings for receiving the elements used in fastening the access plate to the gear box.
